Des. 209,434
Patented Nov. 28, 1967

209,434

TIE HANGER

James Austin Jamison, 6208 Winifred Drive,
Fort Worth, Tex. 76133

Filed Mar. 29, 1967, Ser. No. 6,422

Term of patent 14 years

(Cl. D80—8)

FIG. 1 is a perspective view of a tie hanger showing my new design; and

FIG. 2 is a cross sectional view taken on line 2—2 of FIG. 1.

The fragmentary broken line representations of clip-on ties in FIG. 1 is for purposes of illustration only.

I claim:

The ornamental design for a tie hanger, as shown and described.
